UNITED STATES PATENT OFFICE.

WALTER S. LANDIS, OF WHITESTONE LANDING, NEW YORK, AND GUY H. BUCHANAN, OF WESTFIELD, NEW JERSEY, ASSIGNEES TO AMERICAN CYANAMID COMPANY, OF NEW YORK, N. Y., A CORPORATION OF MAINE.

METHOD OF FUMIGATION.

No Drawing.

Application filed July 8, 1921. Serial No. 483,264.

This invention relates to a method of fumigating with highly poisonous fumigants, and has for its object to improve certain of the methods heretofore proposed 5 and now in wide use to the end that they may be made more efficient and less dangerous than they are as at present practiced.

With these and other objects in view, the invention consists in the novel steps and 10 combinations of steps constituting the method, all as will be more fully disclosed below and particularly pointed out in the claims.

In order that the precise nature of the 15 invention may be the more clearly understood, it is said:

In the fumigation of buildings, ships and other enclosed spaces with hydrocyanic acid gas for the purpose of destroying vermin 20 and other pests, the common practice has been to determine the volume of the space to be fumigated and then to atomize or vaporize into this space a suitable quantity of liquid hydrocyanic acid.

The enclosed space, charged with the fumigant, is permitted to stand for a suitable length of time, usually one or two hours, or even longer in the case of certain 25 special work, and is then opened up and the 30 poisonous fumigant displaced by the admission of fresh air from the outside. Where adequate means of ventilating the enclosed space are at hand, the dissipation of the 35 poisonous fumes is not a difficult problem, but in the case of ships and warehouses from five to twelve hours or longer are usually required to effectually remove the 40 poisonous gas and render the space habitable. The long time necessary for clearing out the hydrocyanic acid fumes where facilities for ventilation are limited, is at times a source of considerable annoyance and expense. In the case of a cargo carrying 45 steamship, for example, it may mean a delay in unloading or re-loading of the ship and a very considerable demurrage charge may accrue due to this tie-up of the vessel.

We have found, however, a simple and 50 expeditious method of destroying the residual hydrocyanic acid so as to eliminate it in a comparatively short time, thereby gaining the use of the space to be fumigated much more quickly than would otherwise be the case.

This method consists briefly in the admission to the space after fumigating, of a volatile aldehyde and steam or water vapor. Aldehyde vapor, such, for example, as that of formaldehyde, reacts only very slowly on dilute gaseous hydrocyanic acid, but if it is in sufficient concentration and is in the presence of water vapor, the reaction takes place relatively rapidly and is remarkably complete. For example, in carrying out this process, we close up the space to be fumigated comparatively tightly, and introduce into this space sufficient hydrocyanic acid for an effective fumigation. This quantity is such as to provide from, say, 0.2 volume per cent up to one volume 55 per cent of hydrocyanic in the space to be fumigated, and the application may be made by generating the gas directly in the space or by using liquid hydrocyanic acid which is applied through one of the several forms 60 of well known applicators which may be provided for this purpose. We leave the space closed for one or two hours or whatever time is necessary, to insure killing of the pests present. At the end of this time, 65 we introduce into said space, for example, to each pound of anhydrous hydrocyanic acid, approximately five pounds of U. S. P. formalin, or its equivalent, in the form of 70 formaldehyde gas. This can be introduced 75 either by atomizing the formaldehyde, or by pouring the same rapidly onto a quantity of permanganate crystals. Along with the formalin or formaldehyde gas, we also introduce a quantity of water vapor, approximately equal to or greater than the quantity 80 of formaldehyde introduced. If steam is available, we may blow live steam directly into the space until a slight fog is produced. Under the foregoing circumstances, the hydrocyanic acid is very quickly destroyed. 85 For example, in our experimental work, we have destroyed the hydrocyanic acid gas in a room containing 5,000 parts of said gas per million down to less than 12 parts per million inside of one hour by this procedure. In the first ten minutes after introduction 90 of the formaldehyde and water vapor, there was only fifty parts per million of hydrocyanic gas left in the room. Without the addition of the water vapor, which in this instance, serves as an accelerator, our experiments have shown that we lose less than one- 95 100 105

third of the hydrocyanic acid in five hours.

It is self-evident that one may vary the procedure as above outlined without departing from the spirit of the invention, and we therefore do not wish to be limited to the above disclosure except as may be required by the claims.

What we claim is:

1. The method of fumigating with a highly poisonous fumigant which consists in introducing hydrocyanic acid gas into the space to be fumigated; and subsequently introducing into said space a volatile aldehyde adapted to normally react relatively

slowly with said gas, together with water vapor adapted to accelerate said reaction, substantially as described.

2. The method of fumigating with a highly poisonous fumigant which consists in introducing hydrocyanic acid gas into the space to be fumigated; and subsequently introducing formaldehyde and water vapor into said space whereby said gas may be destroyed, substantially as described.

In testimony whereof we affix our signatures.

WALTER S. LANDIS.
GUY H. BUCHANAN.
